K. O. WETZEL,
ANCHORING DEVICE,
APPLICATION FILED JUNE 7, 1920.

1,379,065.

Patented May 24, 1921.

INVENTOR:

Kurt O. Wetzel

UNITED STATES PATENT OFFICE.

KURT O. WETZEL, OF LOS ANGELES, CALIFORNIA, ASSIGNOR TO K. O. WETZEL CO.,
OF LOS ANGELES, CALIFORNIA.

ANCHORING DEVICE.

1,379,065.

Specification of Letters Patent. Patented May 24, 1921.

Application filed June 7, 1920. Serial No. 387,079.

To all whom it may concern:

Be it known that I, KURT O. WETZEL, a citizen of the United States, residing at Los Angeles, in the county of Los Angeles and State of California, have invented a new and useful Anchoring Device, of which the following is a specification.

This invention relates to devices embodied in concrete and similarly built-up walls and surfaces by which other articles can be secured or applied to such walls and surfaces without having to cut or work into such walls and surfaces after such walls and surfaces have been finished.

One of the objects of this invention is to save labor in case it becomes necessary to secure or apply other articles to finished concrete walls and surfaces.

Another object is to assure a correct location of means for securing or applying other articles to walls and surfaces.

Another object is to facilitate a securing and applying of other articles to finished walls and surfaces.

Another object is to provide a device which can be secured inside of a mold to be covered by the material when such is filled into the mold.

Another object is to provide a device which can be secured inside of a mold to be covered by the material when such is filled into the mold so as to leave certain parts or portions of the device in such a condition as to allow a securing or applying of other articles to the finished product in the mold without requiring a cutting or working into the material of the finished product.

Another object is to provide a device of this kind of such a shape as to make it easy and to facilitate a securing and applying of other articles by means of this device to concrete and similarly molded materials.

Other objects will appear from the following description and appended claims as well as from the accompanying drawing, in which—

Figure 1 is a front view of the device embodied in other material.

Fig. 2 is a side view of Fig. 1 seen in the direction of the arrows 2—2.

Fig. 3 is a front view of the device slightly modified and with surrounding material.

Fig. 4 is a side view of the cap member 55 of the device illustrated in Fig. 3.

Fig. 5 is a side view of the cap member of a still more slightly modified form.

In concrete buildings as well as when using materials or products of materials built up in a similar manner, it is very desirable to have, at predetermined points or at points where at some future time it may be of use, some means for applying, securing, or fastening some other articles. In buildings, for instance, it occurs very often that fixtures have to be secured to walls or ceilings at some future time at points where they are not at all desired when the building is erected or finished, or where such means may even be in the way or very much inconvenient. With heavy concrete blocks it is very often only a matter of having some means for lifting such blocks into place when erecting, and, later on, such means should not at all show or obstruct. At the same time such means always must be strong enough for the intended purposes. Furthermore, it must be possible and easy to cover up such points where such means are located as long as not used.

It is also important that such means should not shift or get out of shape or form when concrete or similar material is being filled in or built up so as to some extent 85 surround the device.

With this main point in view, and considering other points which naturally follow from the argument occurring in the following description of the device, it becomes necessary to have—first: a cap member, which can easily be placed into a mold so that concrete or other similar material can be disposed around and over it, and, second: some anchoring means for rigidly 90 maintaining a secure engagement with such material after such material becomes a finished product. The cap member then naturally must be of such a form as not to fill or be filled up by such material when such material is poured over it, and there must be and remain some means to which other articles can be secured or applied without obstructing or projecting from finished walls or out of 95 finished surfaces.

The cap 6, illustrated in Fig. 1, is therefore made of a form retaining a hollow space in the surface of the finished product.

if concrete or other similar material is filled in over it from the rear. The cap in the modified form 7, illustrated in Figs. 3 and 4; and the cap in the still more modified form 8, illustrated in Fig. 5, are designed with the same idea in view, and many other still more slightly modified forms can easily be provided without departing from the spirit of this invention.

10 For building up concrete and other similar material, it is normally necessary to provide some forms or molds into which such materials can be poured. Such molds are usually of wood for the sake of cheapness and convenience.

15 The devices are therefore provided with cut-outs 9 and holes or perforations 10. Such means, however, are at such points as to prevent material from getting into the hollow of the device. A flange 11 is therefore preferably provided, having such cut-outs and perforations. Nails 12 of suitable length and strength can then naturally be used to secure the devices to the inside of such molds so as to firmly hold the devices in place while such material is being poured into the mold.

20 Other cut-outs 13 are preferably provided in the device so as to allow a passing of a bar or member 14 through and over the front of the space in the device.

25 The hollow of the cap member is in Fig. 1 in the drawing illustrated as of elongated form, but naturally can be of any other form as long as it allows a handling of the device in the manner described hereafter. The elongated form is, however, preferred for the following reasons: After the device has been embodied into the material as set forth above, it becomes naturally necessary that fastening means must be inserted into the device, that is into the hollow behind the member 14 so as to bring such fastening means around the member 14. If then a 30 wire or any other similar means is pushed into the hollow from eventually the point 15, it follows normally in the path along the deepest portion of the hollow to eventually the point 16 where it comes in contact with the inclined surface so as to be directed upwardly or outwardly of the hollow, then naturally being in a position that it can be pulled around the member 14. The member 14 is not across the hollow at exactly right angles to the longer line through the center of the hollow, since this appears to give the best results. The fastening means can be pushed through in whatever direction it may be tried; it is bound to come out of the hollow behind the member 14, while in the slightly modified forms in Figs. 3, 4 and 5 it eventually may come out of the hollow on the same side of the member 14 at which it has been pushed in if 35 pushed in eventually from a point near the

member 14, which cannot always be controlled, especially when such devices are located at inconvenient points in walls, ceilings and other places, as will easily be understood. The form of the hollow is however not limited as stated before.

40 The member 14 is preferably made in form of an independent anchor member only passing in front of and through the hollow in the cap member, for the reasons stated above.

45 The preferred form of the anchor member is as illustrated in Figs. 1, 2 and 3. From the member 14 two members 17 extend into the material in which the device is being used to a point to warrant a secure holding of the device within the finished product of such material. The ends of the member 14 are bent as indicated at 18 turning back toward the front as indicated at 19 to terminate flush with the front of the cap member 6 as indicated at 20. Bending the ends in the opposite directions tends to serve for bracing the anchor member in itself, as will easily be understood. If such a cap member 6 is fastened temporarily to the side within a mold, one end 19 naturally braces upwardly while the other end 19 braces downwardly, it naturally follows that, if material falls upon the ends, the lower end 19 will brace against such falling material so as to prevent the anchor member from collapsing, and that the anchor will brace itself in any direction no matter if material presses upwardly or downwardly, so that the anchor member will retain its proper form within the material thereby assuring a proper holding of the anchor member within the material after such material has come to form a set condition to rigidly engage the anchor permanently at the same time engaging the cap member within the material.

50 In Fig. 2, the nails 12 are shown sticking out of the cap member. It will easily be understood, without further illustration or explanation, that, having the cap member nailed within the mold, the nails will easily pull out of such of the boards of the mold when the boards are removed from the material after the material has set. Such nails can then be used for securing small ornaments or other similar things if such are to be used at such points, otherwise it is naturally desirable to remove such nails. 55 In cases where the nails are not wanted, they are from the beginning placed in the cut-outs 9 instead of the perforations 10, so that the nails may easily be broken out from under the edge of the cap member, as will easily be understood.

60 The device in the slightly modified form illustrated in Figs. 3 and 4 is of a practically round shape in front view and of nearly half-globular shape as a whole but 65

otherwise of a similar construction as the device in Figs. 1 and 2. The flange 21 is for the same purpose as the flange 11 in Figs. 1 and 2. The anchor member 22 is 5 provided with similar ends 23 projecting in opposite directions terminating flush with the front of the cap member 7.

The slightly modified form illustrated in Fig. 5 is only to illustrate that it is not 10 necessary that the cap member has to be of round form but may just as well be of any other form as long as the sides of the cap member are so shaped that they will deflect and direct any fastening means so as 15 to bring it back out of the cap member when pushed into it from one side in the manner described above. This taper form may be cheaper than the round form in making dies for the manufacture of the cap members; 20 it all depends on what kinds of tools are on hand, and such minor changes are naturally immaterial as far as the principle of the device is concerned.

Having thus described my invention, I 25 claim:

1. In a device of the class described, a body member having an elongated recess in its face, the edges of the body having cut-outs provided in the front face at points 30 diagonally to the elongated recess, the body member being curved away from the edges around the entire periphery of the recess, and an anchor member disposed through such cut-outs in front of the body-recess so 35 as to bring the anchor member flush with the front face of the body and diagonally over the recess in the body.

2. In a device of the class described, a body member having a recess in its face, 40 and an anchor member disposed through and in front of the hollow portion of the body having means projecting rearwardly from the front face of the body adapted to rigidly engage the body and anchor mem-

bers within the surface and flush with the 45 surface of concrete and similar material when so disposed, the anchor member having extension ends curving back from within the surrounding material toward the front to terminate flush with the front face 50 at opposite sides of the centerline passing through the anchor-member in the recessed face of the body-member for bracing the device when material is being poured over and around it.

3. In a device of the class described, a body member having a recess in its face and having means for securing the body to the inside of concrete molds and the like so as to bring the face of the body sealingly to 60 such inside of such mold adapted to allow a removing of nails and other similar means from such mold without damaging the finished concrete, and an anchor member disposed through and in front of the recess in 65 the body having means projecting rearwardly from the front face of the body adapted to rigidly engage the body and anchor members within the surface of material cast into such mold and flush with the 70 surface of such material when finished in the mold, the anchor member having extension ends curving back from within the surrounding material toward the front to terminate flush with the front face at opposite 75 sides of the centerline passing through the anchor-member in the recessed face of the body-member for bracing the device when material is being poured and disposed to engage around the device.

In testimony that I claim the foregoing as my invention I have signed my name in the presence of two subscribing witnesses.

KURT O. WETZEL.
